H. J. ARMSTRONG

CIGARETTE AND MATCH BOX HOLDER

Filed Dec. 5, 1927

Inventor
Harrison J. Armstrong

By Clarence A. O'Brien.
Attorney

UNITED STATES PATENT OFFICE.

HARRISON J. ARMSTRONG, OF ST. LOUIS, MISSOURI.

DESIGN FOR A CIGARETTE AND MATCH-BOX HOLDER.

Application filed December 5, 1927. Serial No. 24,387. Term of patent 3½ years.

To all whom it may concern:

Be it known that I, HARRISON J. ARMSTRONG, a citizen of the United States of America, residing at St. Louis city, Missouri, have invented a new, original, and ornamental Design for a Cigarette and Match-Box Holder, of which the following is a specification, reference being had to the accompanying drawing, forming part thereof.

The figure is a perspective view of a cigarette and match box holder, showing my new design.

I claim:—

The ornamental design for a cigarette and match box holder, as shown.

HARRISON J. ARMSTRONG.
